US00D961614S

(12) United States Design Patent (10) Patent No.: US D961,614 S
(45) Date of Patent: * Aug. 23, 2022

(54) DISPLAY SCREEN OR PORTION THEREOF
WITH ICON

- (71) Applicant: Apple Inc., Cupertino, CA (US)
(72) Inventors: Jesse Boettcher, San Jose, CA (US); Taylor Gerard Carrigan, San Francisco, CA (US); Anton Davydov, Gilroy, CA (US)
(73) Assignee: Apple Inc., Cupertino, CA (US)
() Term: 15 Years
(21) Appl. No.: 29/704,771
(22) Filed: Sep. 6, 2019

Related U.S. Application Data

- (63) Continuation of application No. 29/611,347, filed on Jul. 20, 2017, now Pat. No. Des. 859,438, which is a continuation of application No. 29/510,809, filed on Dec. 3, 2014, now abandoned, which is a continuation of application No. 29/431,548, filed on Sep. 7, 2012, now Pat. No. Des. 725,134.

CLAIM

The ornamental design for a display screen or portion thereof with icon, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with icon showing the claimed design; and,

FIG. 2 is a front view of another embodiment thereof.

The broken lines in the figures show a display screen or portion thereof, and form no part of the claimed design.
